HYDROCYANATION PROCESS

Watari Nagata, Hyogo Prefecture, Japan, assignor to
Shionogi & Co. Ltd., Osaka, Japan
No Drawing. Filed Feb. 26, 1963, Ser. No. 261,215
Claims priority, application Japan, Mar. 2, 1962,
37/8,428

14 Claims. (Cl. 260—239.55)

The present invention relates to a hydrocyanation process generally applicable in the field of organic chemistry, and particularly to a process for introducing a cyano group into the β -position of an α,β -unsaturated ketone. More particularly, it relates to a process which is suitable for the introduction of a cyano group into the angular position of polycyclic compound having an α,β -unsaturated ketone structure of which the β -position corresponds to the said angular position.

The process of the present invention is generally applicable to an organic compound having an α,β -unsaturated ketone structure. However, the advantages of the process can be well exhibited in the cyanation, especially the angular cyanation, of polycyclic compound having an α,β -unsaturated ketone structure.

While the addition of hydrocyanic acid to α,β -unsaturated ketones has been accomplished by various methods, there has been heretofore made no attempt for the direct introduction of a cyano group into the angular position of any polycyclic compound except only two methods, the one relating to the introduction of a cyano group into the 5-position of steroids having a Δ^4 -3-ketone structure by the treatment of the said starting steroids with alkali metal cyanide or alkaline earth metal cyanide in the presence of a hydroxylated organic solvent [Bowers et al.: U.S. Patent 3,050,518] and the other relating to the introduction of a cyano group into the angular position of steroids or D-homosteroids lacking a substituent of the said angular position and possessing an α,β -unsaturated ketone structure of which the β -position corresponds to the said angular position by treating the said starting steroids or D-homosteroids with alkali metal cyanide in the presence of ammonium halide in an inert solvent medium [Nagata et al.: Tetrahedron Letters, No. 17, p. 27 (1960); J. Org. Chem., vol. 26, p. 2413 (1961); Chem. Pharm. Bull., vol. 9, p. 79 (1961)]. However, it has been found that these known methods must be executed under carefully regulated reaction conditions for obtaining the objective angular nitrile in a higher yield, because the once produced angular nitrile is readily hydrolyzed according to the basicity of the employed cyanating agent. Even if careful control is made, it is difficult to inhibit completely the by-production of the hydrolysate of the angular nitrile. The inevitable hydrolysis unfavorably results in the decreased yield of the objective angular nitrile and the contamination of the same with the hydrolysate. It has been also found that the scope for which the said known methods can be applied is limited to a certain extent. For instance, the introduction of a cyano group into the 8-position of steroids or D-homosteroids is unsuccessfully accomplished by them. It has been also found that, according to the said known methods, there has been generally obtained an isomeric mixture of the objective nitrile, in most cases, contaminated with an isomeric mixture of the by-produced hydrolysate. As each of them is usually produced at a considerable amount, the isolation of each compound may be rather troublesome, and it may be impossible to produce only a certain compound of them in a predominant yield. These and other disadvantages of the known methods are now overcome by the process of the present invention.

According to the present invention, the hydrolysis of the once-produced angular nitrile seen in the known

2

methods can be completely inhibited. Therefore, the yield of the objective nitrile is necessarily increased. Adding to this advantage, it may be especially noted that the yield ratio of each isomer, i.e., cis-isomer and trans-isomer, according to the process of the present invention is remarkably one-sided, comparing with that obtained in the known methods. Thus, the process of the present invention may be advantageously adopted, when the production of the trans-form angular nitrile [the angular nitrile wherein the rings on both sides of the cyano group are condensed with each other by a trans juncture] is intended. It may be also noted that the angular cyanation which has never been accomplished by any known methods can be realized by the process of this invention. For instance, the introduction of a cyano group into the 8-position of steroids or D-homosteroids can be successfully carried out. Thus, the process of the present invention has a broader application scope than the known methods have. It may be further noted that the process of the present invention can be executed under a relatively mild reaction condition comparing with the known methods and is applicable to instable compounds. These and other advantages of this invention will be apparent to those conversant with the art to which this invention pertains from the subsequent description.

The process of the present invention comprises reacting an organic compound, especially a polycyclic compound, having an α,β -unsaturated ketone structure substantially with a complex anion represented by the formula:

30 $[AIR'R''CN]^-$ (A)

wherein R represents a lower alkyl group (e.g., methyl, ethyl, propyl, butyl) or a lower alkoxy group (e.g., methoxy, ethoxy, propoxy, butoxy) and R' and R'' each represents a lower alkyl group (e.g., methyl, ethyl, propyl, butyl), a lower alkoxy group (e.g., methoxy, ethoxy, propoxy, butoxy), a halogen atom (e.g., chlorine, bromine) or a cyano group in a substantially anhydrous medium to introduce a cyano group into the position corresponding to the β -position of the α,β -unsaturated ketone structure in the said starting compound.

The complex anion (A) can be produced, for instance by treating an aluminum compound represented by the formula:

45 $AIR'R''$ (B)

wherein R, R' and R'' each has the same significance as designated above with hydrocyanic acid in a substantially anhydrous medium [Equation I] or treating the aluminum compound (B) with an aluminum cyanide compound represented by the formula:

50 $AIR'R'CN$ (C)

wherein R and R' each has the same significance as designated above in a substantially anhydrous medium [Equation II], the aluminum cyanide compound (C) being prepared by treating an aluminum hydride compound represented by the formula:

55 $AIR'R'H$ (D)

wherein R and R' each has the same significance as designated above with hydrocyanic acid in a substantially anhydrous medium [Equation III]. Therefore, the process of the present invention

60 $AIR'R'' + HCN \rightleftharpoons H^+ + [AIR'R''CN]^-$ (I)

$AIR'R'' + AIR'R'CN \rightleftharpoons AIR'R' +$

65 $+ [AIR'R''CN]^-$ (II)

$AIR'R'H + HCN \rightarrow AIR'R'CN + H_2$ (III)

may be actually performed by treating an organic compound, especially a polycyclic compound, having an α,β -unsaturated ketone structure with a combination of hydrocyanic acid or the aluminum cyanide compound (C) with the aluminum compound (B) in a substantially anhydrous medium. As the aluminum compound (B),

there may be exemplified tri(lower)alkyl aluminum, di(lower)alkyl aluminum lower alkoxide, lower alkyl aluminum di(lower)alkoxide, aluminum tri(lower)alkoxide, di(lower)alkyl aluminum halide, lower alkyl aluminum dihalide, di(lower)alkyl aluminum cyanide, lower alkyl aluminum halide cyanide and the like. Examples of the aluminum cyanide compound (C) may be di(lower)alkyl aluminum cyanide, lower alkyl aluminum dicyanide, di(lower)alkoxy aluminum cyanide, lower alkyl aluminum dicyanide, lower alkyl lower alkoxy aluminum cyanide, etc. The aluminum hydride compound (D) may include, for instance, di(lower)alkyl aluminum hydride, lower alkyl lower alkoxy aluminum hydride, di(lower)alkoxy aluminum hydride, lower alkyl aluminum hydride cyanide and the like. Although any complex anion represented by Formula A is effective in the process of the present invention, an alkyl aluminum complex anion of Formula A wherein at least one of R, R' and R'' is a lower alkyl group possesses a relatively high activity. Particularly, a tri(lower)alkyl aluminum cyanide complex anion of Formula A wherein R, R' and R'' each represents a lower alkyl group is very active, and can be the most broadly employed. Otherwise stated, the use of a combination of hydrocyanic acid or a di(lower)alkyl aluminum cyanide of Formula C wherein R and R' each represents a lower alkyl group such as dimethyl aluminum cyanide, diethyl aluminum cyanide, dipropyl aluminum cyanide and dibutyl aluminum cyanide with a tri(lower)alkyl aluminum of Formula B wherein R and R' each represents a lower alkyl group such as trimethyl aluminum, triethyl aluminum, tripropyl aluminum and tributyl aluminum is practically preferred.

As the reaction medium, there may be employed an inert non-polar solvent such as benzene, ether, tetrahydrofuran and dioxane. The presence of water causes unfavorable loss of the said cyanating agent. Therefore, it is preferable that the solvent be dried prior to use.

The reaction may be carried out at a temperature from room temperature (15 to 30° C.) to reflux temperature, preferably around room temperature, for about 0.5 hour to about 100 hours. However, strict control of reaction temperature and reaction time is not necessary.

As the cyanating agent, i.e., the aluminum compound (B), the aluminum cyanide compound (C) and the aluminum hydride compound (D), is generally combustible in atmosphere, the previous replacement of the air in a reaction vessel with an inert gas such as nitrogen is preferred. However, such replacement is not needed, when the cyanating agent is employed in the form of the solution in the said inert solvent.

By the execution of the said cyanation reaction, there may be produced the addition product of the fragments the complex anion (A) to the starting α,β -unsaturated ketone or the hydrocyanic acid adduct of the objective nitrile. However, the former addition product is readily hydrolyzed in the presence or absence of an acid or an alkali, usually in the course of the recovery operation, to give the objective nitrile or the hydrocyanic acid adduct thereof. The latter adduct is also readily hydrolyzed with an aqueous alkaline solution such as sodium hydroxide, potassium hydroxide, sodium carbonate and potassium carbonate to the objective nitrile.

A typical example of the practical procedures for carrying out the process of the present invention is as follows:

An α,β -unsaturated ketone is combined with a mixture of hydrocyanic acid and tri(lower)alkyl aluminum in a substantially anhydrous inert organic solvent medium, and the resultant mixture is allowed to stand at room temperature (15 to 30° C.). After several hours, the reaction mixture is treated with an aqueous alkaline solution while cooling with ice and shake with a water-immiscible organic solvent. The organic solvent phase is washed with water, dried and the solvent removed whereby the corresponding saturated ketone possessing a cyano group at the β -position to the carbonyl group is obtained.

The conversion in the process of the present invention is generally representable by the following partial formulae:

Although the present hydrocyanation process possesses a number of advantageous characteristics as previously stated, it is especially notable that there is produced in general a trans-form angular nitrile [the angular nitrile wherein the rings on both sides of the cyano group are condensed with each other by a trans juncture] predominantly in a good yield, when the process is adopted for the angular cyanation of a polycyclic compound. For comparison, the results obtained by the application of a known hydrocyanation process using potassium cyanide and ammonium chloride in dimethylformamide [Nagata et al.: J. Org. Chem., vol. 26, p. 2413 (1961)] and the present hydrocyanation process using hydrocyanic acid and triethyl aluminum in tetrahydrofuran to various polyisocyclic compounds are shown in the following table:

TABLE

Starting Material	Product	Known Hydrocyanation Process—		Present Hydrocyanation Process—	
		Yield Ratio of Cis:Trans	Total Yield (percent)	Yield Ratio of Cis:Trans	Total Yield (percent)
dl-2,3,4,5,6,7,8b-Octahydronaphthalen-2-one.	dl-2-Oxo-eis and transdecahydronaphthalene-8a-carbonitrile.	1:2	67	1:24	75

dl-3 α -Acetoxy-D-homo-18-nor-5 β -9(11),13(17a)-androstadien-17-one.	dl-3 α -Acetoxy-17-oxo-D-homo-5 β -9(11)-androstene-18-nitrile.			(2)	55
dl-3-Methoxy-18,19-bisnor-1,3,5(10),13(17)-pregnatrien-20-one.	dl-3-Methoxy-20-oxo-19-nor-1,3,5(10)-pregnatriene-18-nitrile and its epimer.	12.5:1	78	1:10 ¹	80
7-Oxocholesterol acetate.	3 β -Acetoxy-7-oxo-5 α -cholestane-5-carbonitrile.	(2)	43	(2)	90
3,3-Ethylenedioxy-17 α -hydroxy-D-homo-18-nor-5,12-androstadien-11-one.	3,3-Ethylenedioxy-17 α -hydroxy-11-oxo-D-homo-5-androstene-18-nitrile.	(2)	90	(2)	73
3 β -Acetoxy-8,22-ergostadien-11-one.	3 β -Acetoxy-11-oxo-5 α -22-ergostane-8-carbonitrile.		0	(2)	70

NOTE: ¹ The yield ratio represents that of an epimer of dl-3-methoxy-20-oxo-19-nor-1,3,5(10)-pregnatriene-18-nitrile:dl-3-methoxy-20-oxo-19-nor-1,3,5(10)-pregnatriene-18-nitrile.

² Trans product alone.

The process of the present invention is valuable as a hydrocyanation process generally applicable to α,β -unsaturated ketones. Especially, it should be noted that the economical process for introducing a cyano group directly to an angular position of polycyclic α,β -unsaturated ketones of which the β -position corresponds to the said angular position is provided by the present invention for the first time. The thus introduced angular cyano group can be converted into a variety of carbon-containing functional groups such as iminomethyl, amino-methyl, hydroxymethyl, formyl, carboxyl, acetyl and methyl. Accordingly, the present invention makes it possible to produce economically a number of known or unknown polycyclic compounds possessing a substituent at the angular position. In the field of steroid chemistry, for instance, it has been well known that the existence of a methyl group or a formyl group at the 13β -position in the steroid nucleus is indispensable for display of effective physiological activities. The cyano group at the angular position of polycyclic compounds can be converted into a formyl group or a methyl group by reducing the angular nitrile with lithium aluminum hydride followed by hydrolysis to the angular aldehyde, which is subjected to hydrazone-formation followed by decomposition with potassium hydroxide to give the angular methyl compound. Therefore, the present hydrocyanation process can be adopted in the synthesis of physiologically active steroids from compounds lacking an angular methyl or formyl group at the position corresponding to the 13β -position of the former. Furthermore, it has been recently disclosed that 5-cyano steroids possess anti-pituitary activity and are useful as anti-estrogenic agents [Bowers et al.: U.S. Patent 3,050,518]. Accordingly, the present hydrocyanation process is also of value in the production of these and other physiologically active steroid angular nitriles.

The following examples set forth illustratively presently-preferred embodiments of the present invention. In these examples, ml.=millilitre(s), g.=gram(s), mg.=milligram(s), and $^{\circ}$ C.=degrees centigrade. Other abbreviations each have conventional significances.

Example 1

To a solution of triethyl aluminum (6.85 g.) in anhydrous tetrahydrofuran (40 ml.) there is added a solution of hydrocyanic acid (1.08 g.) in anhydrous tetrahydrofuran (10 ml.) while cooling with ice in nitrogen atmosphere. The resulting mixture is added to a solution of dl-2,3,4,5,6,7,8,8b - octahydronaphthalen - 2 - one [Bergmann et al.: Bull. Soc. Chem. France, p. 290 (1957)] (3.0 g.) in anhydrous tetrahydrofuran (40 ml.) and allowed to stand for 1 hour at room temperature (15 to 30 $^{\circ}$ C.). The reaction mixture is gradually added to 2 N sodium hydroxide (100 ml.) cooled with ice and shaken with chloroform. The chloroform layer is washed with water, dried and the solvent removed to give the residue (3.46 g.), which is crystallized from a mixture of ether and pentane to obtain dl - 2 - oxo-trans - decahydronaphthalene-8a-carbonitrile (2.137 g.) as crystals melting at 56 to 58 $^{\circ}$ C. The mother liquor is evaporated and the resultant amorphous substance (1.24 g.) chromatographed on alumina (30 g.). The eluate with petroleum ether-benzene (9:1~4:1) is evaporated to give crude dl - 2 - oxo - cis - decahydronaphthalene - 8a-carbonitrile (125 mg.) as an oil. The subsequent eluates with petroleum

ether-benzene (4:1)~benzene are evaporated and crystallized from a mixture of ether and pentane to give dl-2-oxo-trans - decahydronaphthalene - 8a - carbonitrile (389 mg.). The mother liquor and the above obtained oily dl-2-oxo-cis-decahydronaphthalene-8a - carbonitrile are combined together and subjected to semicarbazone formation according to a per se conventional procedure whereby dl-2-oxo-cis-decahydronaphthalene-8a - carbonitrile semicarbazone (147 mg.) is obtained as crystals melting at 204 to 207 $^{\circ}$ C. (crystallized from a mixture of chloroform and methanol).

Example 2

To a solution of dl-7 α -acetoxy-2,3,4,5,6,7,8,9,10,12,13,14 - dodecahydrophenanthren - 2 - one (12 β ,13 α ,14 β) (1.03 g.) in anhydrous tetrahydrofuran (15 ml.), there are added a solution of hydrocyanic acid (165 mg.) in anhydrous tetrahydrofuran (1.45 ml.) and a solution of triethyl aluminum (1.36 g.) in anhydrous tetrahydrofuran (10 ml.) while cooling with ice, and the resultant mixture is allowed to stand for 1.5 hours at room temperature (15 to 30 $^{\circ}$ C.) in nitrogen atmosphere. The reaction mixture is added to 2 N sodium hydroxide (20 ml.) cooled with ice and shaken with ether and chloroform in order. The ether extract and the chloroform extract are combined together, washed with 2 N hydrochloric acid and water in order, dried over anhydrous sodium sulfate and the solvent removed to give the crystalline residue (1.074 g.). The residue is crystallized from acetone to give dl-7 α -acetoxy - 2 - oxotetradecahydrophenanthrene-11 α -carbonitrile (76 mg.) as crystals melting at 149 to 151 $^{\circ}$ C. The mother liquor is evaporated. The residue (968 mg.) is combined with ethyleneglycol (25 ml.) and p-toluenesulfonic acid (30 mg.), heated for 10 minutes in an oil bath (bath temperature, 120 $^{\circ}$ C.) and then condensed under reduced pressure. The condensate is shaken with chloroform. The chloroform extract is washed with dilute aqueous sodium hydroxide, dilute hydrochloric acid and water in order and the solvent removed to give an oily substance (965 mg.). The oily substance is combined with pyridine (3 ml.) and acetic anhydride (1 ml.), allowed to stand at room temperature (15 to 30 $^{\circ}$ C.) overnight and treated according to an ordinary separation procedure to give the crystalline substance (1.074 g.), which is crystallized from a mixture of methanol and chloroform (4:1) to obtain dl - 7 α - acetoxy-2-oxotetradecahydrophenanthrene-11 α -carbonitrile ethyleneketal (322 mg.) as crystals melting at 167 to 168 $^{\circ}$ C. The mother liquor is chromatographed on alumina whereby dl-7 α -acetoxy-2-oxotetradecahydrophenanthrene - 11 α - carbonitrile ethyleneketal (314 mg.), dl - 7 α - acetoxy - 2 - oxotetradecahydrophenanthrene - 11 β - carbonitrile ethyleneketal (78 mg.) as crystals melting at 195 to 202 $^{\circ}$ C. and a mixture thereof (147 mg.) are obtained. When each of the above obtained ketals is hydrolyzed by heating with 70% acetic acid on a steam bath for 20 minutes, there is obtained the corresponding free oxo compound, i.e., dl-7 α -acetoxy-2-oxotetradecahydrophenanthrene-11 α -carbonitrile as crystals melting at 150 to 152 $^{\circ}$ C. and dl-7 α -acetoxy-2-oxotetradecahydrophenanthrene-11 β -carbonitrile as crystals melting at 190 to 196 $^{\circ}$ C. The starting material of this example, dl-7 α -acetoxy-2,3,4,5,6,7,8,9,10,12,13,14 - dodecahydrophenanthren - 2 - one (12 β ,13 α ,14 β), is prepared from 6-methoxy-2-tetra-

lone [Nagata et al.: Tetrahedron Letters, No. 17, p. 27 (1960)] according to the following scheme:

Example 3

To a solution of diethyl aluminum chloride (4.20 g.) in anhydrous tetrahydrofuran (16 ml.), there is added a solution of hydrocyanic acid (675 mg.) in anhydrous tetrahydrofuran (6 ml.) while cooling with ice in nitrogen atmosphere. The resultant mixture is added to a solution of dl-1-oxo-7-methoxy-1,2,3,4,9,10-hexahydrophenanthrene [Stork et al.: J. Am. Chem. Soc., vol 69, p. 2936 (1947) (1.14 g.) in anhydrous tetrahydrofuran (5 ml.) and allowed to stand for 47 hours at room temperature (15 to 30°C.). 2 N sodium hydroxide (40 ml.) is dropwise added to the reaction mixture while cooling with ice and shaken with ether. The ether extract is washed with water and evaporated to give the residue (1.30 g.), which is crystallized from a mixture of acetone and ether to give dl-1-oxo-7-methoxy-1,2,3,4,9,10-hexahydrophenanthrene-4αα-carbonitrile (188 mg.) as crystals melting at 150 to 152°C. The mother liquor is evaporated. The amorphous residue (1.20 g.) is dissolved in ethanol (16 ml.), combined with a solution of semicarbazide hydrochloride (640 mg.) and anhydrous sodium acetate (710 mg.) in water (4.5 ml.) and refluxed for 2 hours. The precipitates are collected by filtration to give a semicarbazone (677 mg.) as crystals melting at 223 to 228°C. The mother liquor is evaporated, and the amorphous sub-

stance (746 mg.) is chromatographed on alumina (22 g.) and eluted with chloroform-methanol (99:1) to give a semicarbazone (130 mg.) as crystals melting at 222 to 230°C. The semicarbazone is combined with the previously obtained semicarbazone and refluxed with a mixture of 2 N hydrochloric acid (60 ml.) and benzene (40 ml.) for 2 hours. The reaction mixture is shaken with ether. The ether extract is washed with 2 N sodium carbonate, ice-water and saturated aqueous sodium chloride in order and evaporated to give the residue (623 mg.), which is crystallized fractionally from a mixture of acetone and ether to obtain dl-1-oxo-7-methoxy-1,2,3,4,9,10-hexahydrophenanthrene-4αα-carbonitrile (221 mg.) as crystals melting at 150 to 152°C. and dl-1-oxo-7-methoxy-1,2,3,4,9,10-hexahydrophenanthrene-4αβ-carbonitrile (31 mg.) as crystals melting at 128 to 130°C.

8

Example 4

To a solution of triethyl aluminum (9.61 g.) in tetrahydrofuran (65 ml.), there is added dropwise a solution of hydrocyanic acid (1.52 g.) in tetrahydrofuran (10 ml.) while cooling with ice. To the resultant mixture, there is added a solution of 1,1,4αβ-trimethyl-1,2,3,4,10,4βα,5,6,7,9,4αβ10αα-dodecahydrophenanthren-7-one [Barltrop et al.: J. Chem. Soc., p. 2566 (1958)] (3.458 g.) in tetrahydrofuran (35 ml.) while cooling with ice, and the resulting mixture is allowed to stand at room temperature (15 to 30°C.) for 18 hours. The reaction mixture is portionwise added to a mixture of 4 N sodium hydroxide (40 ml.) and ice and then shaken with chloroform. The chloroform layer is washed with 2 N sodium hydroxide cooled with ice and water in order, dried over anhydrous sodium sulfate and the solvent removed under reduced pressure. The residue is crystallized from methanol to give 1,1,4αβ-trimethyltetradecahydrophenanthren-7-one-8αβ-carbonitrile (2.287 g.) as crystals melting at 144 to 144.5°C.

RI: $\nu_{\text{max}}^{\text{OCH}_3}$ 2245, 1723 cm.⁻¹

Analysis.—Calcd. for C₁₈H₂₇ON: C, 79.07; H, 9.95; N, 5.12. Found: C, 78.66; H, 9.85; N, 5.23.

Example 5

To a solution of 3β-acetoxy-5,16-pregnadien-20-one [Gould: U.S. Patent 2,752,370] (372 mg.) in tetrahydrofuran (4 ml.), there are added a solution of triethyl alumi-

num (343 mg.) in tetrahydrofuran (2 ml.) and a solution of hydrocyanic acid (54.1 mg.) in chloroform (0.5 ml.), and the resultant mixture is allowed to stand at room temperature (15 to 30° C.) for 2.5 hours. The reaction mixture is added to a mixture of 2 N sodium hydroxide and ice and then shaken with ether. The ether layer is washed with 2 N hydrochloric acid and water, dried over anhydrous sodium sulfate and the solvent removed to give the residue which is crystallized from a mixture of acetone and ether to obtain 3 β -acetoxy-20-oxo-5-pregnene-16 α -carbonitrile (262 mg.) as crystals melting at 190 to 1940 C.

Example 6

To a solution of 4-cholesten-3-one [Butenandt et al.: Chem. Ber., vol. 69, p. 882 (1936)] (10 g.) in anhydrous tetrahydrofuran (50 ml.), there are added a solution of hydrocyanic acid (1.05 g.) in anhydrous tetrahydrofuran (20 ml.) and a solution of triethyl aluminum (8.9 g.) in anhydrous tetrahydrofuran (125 ml.) while cooling with ice, and the resultant mixture is allowed to stand at room temperature (15 to 30° C.) for 3 hours in nitrogen atmosphere. The reaction mixture is gradually added to 2 N sodium hydroxide (100 ml.) and shaken with ether. The ether extract is washed with 2 N hydrochloric acid and water in order, dried over anhydrous sodium sulfate and the solvent removed. The residue (11.2 g.) is crystallized from ethanol to give 3-oxo-5 α -cholestane-5-carbonitrile (3.67 g.) as crystals melting at 170 to 180° C. The mother liquor is chromatographed on alumina to give the additional crystals (4.835 g.) of 3-oxo-5 α -cholestane-5-carbonitrile, 3-oxo-5 β -cholestane-5-carbonitrile (2.346 g.) as crystals melting at 112 to 122° C., the hydrolysate of 3-oxo-5 β -cholestane-5-carbonitrile (596 mg.) as crystals melting at 196 to 198° C. and the mixture with the hydrolysate of 3-oxo- α -cholestane-5-carbonitrile (956 mg.).

Example 7

To a solution of triethyl aluminum (400 mg.) in anhydrous benzene (20 ml.), there are added hydrocyanic acid (0.15 ml.) and 4-cholesten-3-one (500 mg.) while cooling with ice, and the resultant mixture is allowed to stand at room temperature (15 to 30° C.) overnight. A small amount of methanol is added to the reaction mixture for decomposition of excess of triethyl aluminum. After addition of 2 N sodium hydroxide (20 ml.) while cooling with ice, the benzene layer is separated. The water layer is shaken with ether and the ether layer combined with the above separated benzene layer. The combined organic solvent layer is washed with water, dilute hydrochloric acid and water in order, dried and evaporated under reduced pressure. The residue (577 mg.) is

chromatographed on alumina (15 g.). The eluates with petroleum ether-benzene (4:1~2:1)~benzene are crystallized from ethanol to give 3-oxo-5 β -cholestane-5-carbonitrile (262 mg.) as crystals melting at 117 to 121° C. and 3-oxo-5 α -cholestane-5-carbonitrile (197 mg.) as crystals melting at 175 to 185° C.

Example 8

To a solution of 19-nortestosterone acetate (17 β -acetoxy-4-estren-3-one) [Birch: J. Chem. Soc., p. 367 (1950)] (20.60 g.) in anhydrous tetrahydrofuran (30 ml.), there is added a solution of triethyl aluminum (18.6 g.) and hydrocyanic acid (2.65 g.) in anhydrous tetrahydrofuran (120 ml.) while cooling with ice, and the resultant mixture is allowed to stand at room temperature (15 to 30° C.) for 1 hour in a vessel provided with a tube of calcium chloride. The reaction mixture is dropwise added to 2 N sodium hydroxide (500 ml.) cooled with ice and then shaken with a mixture of chloroform and ether (4:1). The extract is washed with dilute aqueous sodium hydroxide and water in order, dried over anhydrous sodium sulfate and the solvent removed under reduced pressure. The residue is crystallized from acetone to give 17 β -acetoxy-3-oxo-5 α -estrane-5-carbonitrile (14.5 g.) as crystals melting at 209 to 211° C. The mother liquor is chromatographed to give a small amount of 17 β -acetoxy-3-oxo-5 β -estrane-5-carbonitrile melting at 213 to 214° C.

Example 9

To a solution of dl-3 β -acetoxy-D-homo-18-nor-5 α -13(17a)-andosten-17-one (480 mg.) in anhydrous tetrahydrofuran (6 ml.), there are added 17.2% triethyl aluminum solution in tetrahydrofuran (3.4 ml.) and 15.3% hydrocyanic acid solution in tetrahydrofuran (0.6 ml.) while cooling with ice, and the resultant mixture is allowed to stand for 2.5 hours at room temperature (15 to 30° C.). The reaction mixture is added to ice water alkalinized with 2 N sodium hydroxide and shaken with a mixture of ether and chloroform (3:1). The extract is washed with 2 N sodium hydroxide and aqueous sodium chloride in order, dried over anhydrous sodium sulfate and the solvent removed. The crystalline residue is crystallized from a mixture of chloroform and acetone (1:2) to give dl-3 β -acetoxy-17-oxo-D-homo-5 α -androstane-18-nitrile (302 mg.) as crystals melting at 223 to 225° C. The mother liquor is chromatographed on neutral alumina (4 g.). From the eluate with petroleum ether-benzene

11

(5:5), there is obtained dl- β -acetoxy-17-oxo-D-homo- Δ_5 , 13α -androstane-18-nitrile (29 mg.) as crystals melting at 227 to 233° C. From the subsequent eluates with petroleum ether-benzene (3:7) benzene-~benzene-chloroform (9:1~5:5), there is obtained dl- β -acetoxy-17-oxo-D-homo- 5α -androstane-18-nitrile (19 mg.). The uncryallized portion (159 mg.) on the above chromatography is combined with ethyleneglycol (50 ml.) and p-toluenesulfonic acid hydrate (5 mg.), refluxed for 1 hour on an oil bath (bath temperature, 100° C.) under reduced pressure and then condensed under more reduced pressure to a $\frac{1}{10}$ volume. The condensate is added to a mixture of 2 N sodium carbonate and ice and shaken with chloroform. The chloroform extract is washed with water, dried and evaporated to give an oily residue (161 mg.), which is chromatographed on neutral alumina (8 g.). From the eluate with petroleum ether-benzene (4:6), the eluates with petroleum ether-benzene (3:7~2:8)-~benzene, the eluate with benzene-chloroform (7:3) and the eluate with benzene-chloroform (5:5), there are obtained dl- β -acetoxy-17-oxo-D-homo- 5α -androstane-18-nitrile ethyleneketal (19 mg.) as crystals melting at 235 to 237° C. dl- β -acetoxy-17-oxo-D-homo- 5α , 13α -androstane-18-nitrile ethyleneketal (24 mg.) as crystals melting at 221 to 226° C., dl- β -hydroxy-17-oxo-D-homo- 5α , 13α -androstane-18-nitrile ethyleneketal (18 mg.) as crystals melting at 222 to 223° C. and dl- β -hydroxy-17-oxo-D-homo- 5α -androstane-18-nitrile ethyleneketal (16 mg.) as crystals melting at 209 to 212° C., respectively.

The starting material of this example, dl-3- β -acetoxy-D-homo-18-nor-5 α -13(17a)-androsten-17-one, is prepared from 6-methoxy-2-tetralone according to the following scheme:

12

hydroxy-20-oxo-5 α -16-pregnene-ene 3-acetate according to the following scheme, the latter being well-known as an intermediate in the synthesis of cortical hormones [e.g., Wall: U.S. Patent 2,666,770; Buck et al.: U.S. Patent 2,678,932];

The product of this example, $\text{dl-3}\beta\text{-acetoxy-17-oxo-D-homo-5}\alpha\text{-androstane-18-nitrile}$, can be converted into 3β - 75

13

10

14

according to a conventional recovery procedure to give the residue, which is chromatographed on neutral alumina. From the eluate with petroleum ether-benzene, there is obtained 3,3:17,17-bisethylenedioxy-5 β -9(11)-5 androstene-5-carbonitrile (118 mg.) as crystals melting at 191 to 192.5° C. From the subsequent eluate with benzene-chloroform, there is obtained 3,3:17,17-bisethylenedioxy-5 α -9(11)-androstene-5-carbonitrile (7 mg.) as crystals melting at 236 to 238° C.

15

Example 11

35

To a solution of dl-3 α -acetoxy-D-homo-18-nor-5 β -9(11),13(17a)-androstadien-17-one (240 mg.) in anhydrous tetrahydrofuran (3 ml.), there is dropwise added a solution of triethyl aluminum (0.45 ml.) and hydrocyanic acid (0.52 ml.) in anhydrous tetrahydrofuran (7 ml.) while cooling with ice, and the resultant solution is allowed to stand for 2 hours at room temperature (15 to 30° C.). After addition of a small amount of methanol to the reaction mixture for decomposing excess of the reagent, the resultant mixture is poured into cold 2 N hydrochloric acid and shaken with a mixture of ether and chloroform (3:1). The extract is washed with 2 N sodium hydroxide and water in order, dried over anhydrous sodium sulfate and evaporated under reduced pressure. The thus-obtained residue is crystallized from a mixture of acetone, ether and pentane to give the crystals (111 mg.) melting at 240 to 251° C. The mother liquor is chromatographed on neutral alumina whereby the additional crystals (10 mg.) are obtained. Both crystals are combined together and recrystallized from a mixture of acetone and ether to give dl-3 α -acetoxy - 17 - oxo - D - homo-5 β -9(11)-androstene-18-nitrile as crystals melting at 249 to 251° C.

Analysis.—Calcd. for C₂₂H₂₈O₃N: C, 74.33; H, 8.22; N, 3.94. Found: C, 74.31; H, 8.26; N, 3.92.

55 The starting material of this example, dl-3 α -acetoxy-D-homo-18-nor-5 β -9(11),13(17a)-androstadien-17-one, is prepared from dl-17-methoxy-D-homo-18-nor-4,8,13,15,17-androstanapentaen-3-one [cf. Example 9 of the present specification] according to the following scheme:

60

70

65

75

To a solution of triethyl aluminum (1.93 ml.) in anhydrous tetrahydrofuran (20 ml.), there are added a solution of hydrocyanic acid (270 mg.) in anhydrous tetrahydrofuran (2.37 ml.) and a solution of 4,9(11)-androstadiene-3,17-dione [Heyl et al.: J. Am. Chem. Soc., vol. 77, p. 488 (1955)] (4 g.) in anhydrous tetrahydrofuran (20 ml.), and the resultant mixture is allowed to stand for 4 hours at room temperature (15 to 30° C.). The reaction mixture is added to a mixture of 2 N sodium hydroxide and ice and shaken with a mixture of ether and chloroform (2.5:1). The extract is washed with 2 N sodium hydroxide and aqueous sodium chloride in order while cooling at 0° C., dried over anhydrous sodium sulfate and evaporated under reduced pressure. The residue (1.12 g.) is crystallized from methanol to give 3,17-dioxo-5 α -9(11)-androstene-5-carbonitrile (830 mg.) as crystals melting at 249 to 255° C. The mother liquor is evaporated to dryness to give an amorphous substance (263 mg.). The amorphous substance is combined with p-toluenesulfonic acid hydrate (13 mg.) and ethyleneglycol (10 ml.) and heated for 1.5 hours at 80° C. The resulting mixture is neutralized with ethanolic potassium hydroxide, poured onto ice-water and shaken with chloroform. The chloroform extract is treated ac-

75

The product of this example, dl-3 α -acetoxy-17-oxo-D-homo-5 β -9(11)-androstene-18-nitrile, can be converted into dl-3 α -acetoxy-5 β -9(11),16-pregnadien-20-one according to the following scheme, the latter being readily converted into cortisone in a per se conventional manner [Callow et al.: J. Chem. Soc., p. 4739 (1956); Kritchevsky et al.: J. Am. Chem. Soc., vol. 74, p. 483 (1952)]:

21
Example 15

To a solution of triethyl aluminum (421 mg.) in ether (1.50 g.), there are added a solution of hydrocyanic acid (217 mg.) in ether (1.00 g.) while cooling with ice and then a solution of 7-oxocholesterol acetate (500 mg.) in ether (20 ml.). The resultant mixture is allowed to stand at room temperature (15 to 30° C.) for 48 hours. After addition of a small amount of methanol to the reaction mixture for decomposing excess of the reagent, the resulting mixture is poured onto ice-water and shaken with ether. The ether extract is washed with 2 N sodium hydroxide, water, 2 N hydrochloric acid and water in order, dried over anhydrous sodium sulfate and evaporated to give the residue (537 mg.), which is crystallized from a mixture of methanol and ether to obtain 3 β -acetoxy-7-oxo-5 α -cholestane-5-carbonitrile (306 mg.) as plates melting at 197 to 200° C. The mother liquor is chromatographed whereby the additional crystals (166 mg.) of the same compound are obtained.

Example 16

To a solution of 3,3-ethylenedioxy-17 α -hydroxy-D-homo-18-nor-5,12-androstadien-11-one (286 mg.) in tetrahydrofuran (25 ml.), there is added a solution of triethyl aluminum (2.34 ml.) and hydrocyanic acid (1.02 ml.) in tetrahydrofuran (5 ml.), and the resultant mixture is allowed to stand at room temperature (15 to 30° C.) for 25 hours. After addition of ice for decomposing the reagent, the reaction mixture is poured onto 2 N sodium hydroxide while cooling with ice and shaken with chloroform. The chloroform extract is washed with 2 N sodium hydroxide and water in order while cooling with ice, dried over anhydrous sodium sulfate and evaporated under reduced pressure. The thus-obtained crystalline residue (314 mg.) is crystallized from a mixture of dichloromethane and methanol to give 3,3-ethylenedioxy-17 α -hydroxy-11-oxo-D-homo-5-androsten-18-nitrile (227 mg.) as crystals melting at 237 to 239° C.

The starting material of this example, 3,3-ethylenedioxy-17 α -hydroxy-D-homo-18-nor-5,12-androstadien-11-one, is prepared from 4-androstene-3,11,

22
17-trione 17-oxime [Nagata et al.: U.S. Patent 3,055,917] according to the following scheme:

The product of this example, 3,3-ethylenedioxy-17 α -hydroxy-11-oxo-D-homo-5-androsten-18-nitrile, can be converted into 3,20-dioxo-11 β ,21-dihydroxy-4-pregnene-18-oic acid (11-18) lactone 21-acetate according to the following scheme, the latter being a known compound and useful as an intermediate in the synthesis of mineral corticoids [Von Euw et al.: Helv. Chim. Acta, vol. 38, p. 1423 (1955)]:

23

24

Example 17

To a solution of 11-oxo-8,9-dehydrotigogenin acetate [Djerassi et al.: J. Am. Chem. Soc., vol. 75, p. 3496 (1953)] (200 mg.) in anhydrous tetrahydrofuran (6 ml.), there are added a solution of hydrocyanic acid (81 mg.) in anhydrous tetrahydrofuran (0.72 ml.) and a solution of triethyl aluminum (490 mg.) in anhydrous tetrahydrofuran (3.4 ml.), and the resultant solution is allowed to stand at room temperature (15 to 30° C.) overnight in a vessel with stopper. The reaction mixture is poured onto ice-water containing a small amount of sodium hydroxide and shaken with chloroform. The chloroform extract is washed with water, dried and the solvent evaporated in vacuo. The crystalline residue (225 mg.) is crystallized from a mixture of chloroform and methanol to give 8-cyano-11-oxotigogenin acetate (114 mg.) as crystals melting at 300 to 302° C. The mother liquor is chromatographed on alumina and eluted with benzene-chloroform (9:1) whereby a small amount of the addi-

tional crystals of the same substance is obtained. $[\alpha]_D^{22} -12.8 \pm 2^\circ$ (CHCl_3).

Analysis.—Calcd. for C₁₉H₂₈O₃N₂S: C, 62.62; H, 7.74; N, 7.69. Found: C, 62.77; H, 7.80; N, 7.56.

The starting material of this example, 1-methyl-1,2,3,4,4b,5,6,7,9,10-dehydro-1,4a(10aH)-methanoiminomethanophenanthren-7-one N-methanesulfonate, is pre-

pared from dl-1-oxo-7-methoxy-1,2,3,4,9,10-hexahydrophenanthrene [Stork et al.: J. Am. Chem. Soc., vol. 69, p. 2936 (1947)] according to the following scheme:

The product of this example, 1-methyl-8 α -cyano-1,2,3,4,4b,5,6,7,8,8a,9,10 - dodecahydro-1,4a(10aH)-methanoiminomethanophenanthren-7-one N-methanesulfonate, is useful as an intermediate in the synthesis of a naturally existing alkaloid, atisine.

What is claimed is:

35 1. A process which comprises reacting a polyhydro-
polycyclic α,β -unsaturated ketone with a complex anion
of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium to introduce a cyano group into the position corresponding to the β -position to the carbonyl group.

2. A process according to claim 1, wherein the reaction is carried out at a temperature from room temperature to reflux temperature.

3. A process according to claim 1, at least one of R,
50 R' and R'' being lower alkyl.

4. A process which comprises reacting polyhydropoly-cyclic α,β -unsaturated ketone of which the β -position

corresponds to an angular position with complex anion of the formula: $[AlR'R''CN]^-$

wherein R is a member selected from the group consisting of lower alkyl and lower alkoxy and R' and R" each is a member selected from the group consisting of lower alkyl, lower alkoxy, halogen and cyano in a substantially anhydrous medium to introduce a cyano group into the said angular position.

5. A process which comprises reacting D-homo-steroid having α, β -unsaturated ketone structure of which the β -position corresponds to an angular position with complex anion of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium at a temperature from room temperature to reflux temperature to introduce a cyano group into the said angular position.

75 6. A process which comprises reacting 2,3,4,5,6,7,

8,8b-octahydronaphthalen-2-one with complex anion of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium at a temperature from room temperature to reflux temperature to introduce a cyano group into the 8a-position.

7. A process which comprises reacting polyhydrotrisocyclic α,β -unsaturated ketone of which the β -position corresponds to an angular position with a complex anion of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium at a temperature from room temperature to reflux temperature to introduce a cyano group into the said angular position, the polyhydrotrisocyclic α,β -unsaturated ketone being a member selected from the group consisting of 7 α -acetoxy-2,3,4,5,6,7,8,9,10,12,13, 14-dodecahydrophenanthrene-2-one, 1 - oxo-7-methoxy-1,2,3,4,9,10 - hexahydrophenanthrene and 1,1,4a β -trimethyl - 1,2,3,4,4a β ,4b α , 5,6,7,9,10,10a α -dodecahydrophenanthren-7-one.

8. A process which comprises reacting polyhydrotetrasisocyclic α,β -unsaturated ketone of which the β -position corresponds to an angular position with a complex anion of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium at a temperature from room temperature to reflux temperature to introduce a cyano group into the said angular position, the polyhydrotetrasisocyclic α,β -unsaturated ketone being a member selected from the group consisting of 4-cholest-3-one, 19-nortestosterone acetate, 3 α - acetoxy-D-homo-18-nor-5 α -13(17 α -androst-17-one, 4,9(11)-androstadiene-3,17-dione, 3 α -acetoxy-D-homo-18 - nor-5 α -9(11),13(17 α)-androstadien-17-one, 3-methoxy-18,19-bisnor-1,3,5(10),13(17)-pregnatetra-20-one, 7-oxocholesterol acetate, 3,3-ethylenedioxy-17 α -hydroxy - D - homo-18-nor-5,12-androstadien-11-one, 11 - oxo-8,9 - dehydrotigogenin acetate, 3 β -acetoxy-5 α -pregnen - 11,20 - dione, 3 α -acetoxy-8,22-ergostadien-11-one, 3,3:17,17 - bis - ethylenedioxy-5,8-androstadien-11-one and 17,20:20,21 - bismethylenedioxy-3,3-ethylenedioxy-5,8-pregnadien-11-one.

9. A process which comprises reacting 1-methyl-1,2,3,4,4b,5,6,7,9,19-decahydro - 1,4a(10aH) - methanoimino-methanophenanthren - 7 - one N-methanesulfonate with complex anion of the formula:

[AIRR'R''CN]-

wherein R is a member selected from the group consisting of lower alkyl and lower alkoxy and R' and R'' each is a member selected from the group consisting of lower alkyl, lower alkoxy, halogen and cyano in a substantially anhydrous medium at a temperature from room temperature to reflux temperature to introduce a cyano group into the 8a-position.

10. A process which comprises intermixing polyhydrotrisocyclic α,β -unsaturated ketone in a substantially an-

hydrous medium with an aluminum compound of the formula:

AIRR'R"

wherein R is a member selected from the group consisting of lower alkyl and lower alkoxy and R' and R'' each is a member selected from the group consisting of lower alkyl, lower alkoxy, halogen and cyano and with a member selected from the group consisting of hydrocyanic acid and an aluminum cyanide compound of the formula:

AIRR'CN

wherein R, R' and R'' each has the same significance as designated above, whereby in ensuing reaction a cyano group is introduced into said ketone in the β -position to the carbonyl group.

11. A process which comprises intermixing polyhydrotrisocyclic α,β -unsaturated ketone of which the β -position corresponds to an angular position in a substantially anhydrous medium with an aluminum compound of the formula:

AIRR'R"

wherein R is a member selected from the group consisting of lower alkyl and lower alkoxy and R' and R'' each is a member selected from the group consisting of lower alkyl, lower alkoxy, halogen and cyano and with a member selected from the group consisting of hydrocyanic acid and an aluminum cyanide compound of the formula:

AIRR'CN

wherein R, R' and R'' each has the same significance as designated above, whereby in ensuing reaction a cyano group is introduced into said ketone in said angular position, hydrolysis of the resultant angular nitrile being inhibited.

12. The process according to claim 10, which is followed by treatment of the resulting product with a member selected from the group consisting of aqueous acidic solution and aqueous alkaline solution.

13. A process which comprises intermixing a member selected from the group consisting of cyclopentanopolypolyhydrophenanthrenes and cyclohexanopolypolyhydrophenanthrenes having an α,β -unsaturated ketone structure of which the β -position corresponds to an angular position and an aluminum compound of the formula:

AIRR'R"

wherein R is a member selected from the group consisting of lower alkyl and lower alkoxy and R' and R'' each is a member selected from the group consisting of lower alkyl, lower alkoxy, halogen and cyano and with a member selected from the group consisting of hydrocyanic acid and an aluminum cyanide compound of the formula:

AIRR'CN

wherein R, R' and R'' each has the same significance as designated above, whereby in ensuing reaction a cyano group is introduced into said polyhydrophenanthrene in said angular position.

14. A process according to claim 13, wherein the α,β -unsaturated ketone is a $\Delta^{8,9}$ -11-keto compound and the cyano group is introduced into the 8-position.
